(57) **CLAIM**

The ornamental design for an instrument holster, as shown.

DESCRIPTION

FIG. 1 is a perspective view of an instrument holster showing our new design;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a top plan view thereof;

FIG. 7 is a bottom plan view thereof; and,

FIG. 8 is a perspective view thereof shown with broken lines removed.

The broken lines shown in the figures are for illustrative purposes only and form no part of the claimed design.
